(57) **CLAIM**

I claim the ornamental design for a light bulb-shaped flashlight, as shown and described.

DESCRIPTION

FIG. 1 is a perspective view of a light bulb-shaped flashlight.

FIG. 2 is a front view of the light bulb-shaped flashlight.

FIG. 3 is a back view of the light bulb-shaped flashlight.

FIG. 4 is a first side view of the light bulb-shaped flashlight.

FIG. 5 is a second side view of the light bulb-shaped flashlight.

FIG. 6 is a top view of the light bulb-shaped flashlight; and,

FIG. 7 is a bottom view of the light bulb-shaped flashlight. The bulb, the activation switch, the annular edge dividing line, the components under the push tab, and other components that are shown in broken lines form no part of the claimed design.
